UNITED STATES PATENT OFFICE.

ORVILLE R. VAN VECHTEN, OF BROOKLYN, NEW YORK.

SEWING-MACHINE.

SPECIFICATION forming part of Letters Patent No. 272,104, dated February 18, 1883.

Application filed May 3, 1882. (No model.)

To all whom it may concern:

Be it known that I, ORVILLE R. VAN VECHTEN, a citizen of the United States, residing in the city of Brooklyn, county of Kings, and State of New York, have invented certain new and useful Improvements in Sewing-Machines, fully described and represented in the following specification and the accompanying drawings, forming a part of the same.

10 The present invention relates to a sewing-machine of the same general construction as that shown in United States Patents No. 246,644 and No. 256,518.

The machine shown and described in those 15 patents is designed and adapted for sewing together the mouths of bags, or for uniting the edges of short pieces of fabric, which can readily be held between the bars of a clamping-frame, such as shown in said patents. The machine thus shown is, however, for various reasons, not fitted for use in uniting the edges of long pieces of fabric, and consequently the field of its usefulness is comparatively limited.

It is the object of the present invention to 25 adapt this machine for use in sewing together long pieces of material, and particularly breadths of carpeting and like heavy fabrics, which cannot be operated upon by an ordinary sewing-machine.

30 To that end the invention consists in various details of construction, both singly and in combination, as will hereinafter be fully explained and pointed out.

In said drawings, Figure 1 is a plan view of 35 a mechanism such as shown in the patents referred to, but modified so as to embody the present invention. Fig. 2 is a transverse vertical section of the same, taken upon the line $x\ x$ of Fig. 1. Fig. 3 is a vertical section 40 taken upon the line $x\ x$ of Fig. 2. Fig. 4 is a horizontal section taken on the line $y\ y$ of Fig. 2. Fig. 5 is a transverse vertical section taken upon the line $z\ z$ of Fig. 1. Figs. 6 and 7 are end and side views of a gage for properly adjusting the edges of the material preparatory 45 to sewing them together.

In using the machine, modified as herein shown, the edges of the fabric to be united, instead of being clamped between the bars of 50 a clamping-frame, as in the patents referred to, are impaled upon the pins 1, which project

from the edge of a table or counter, 2, which will be of sufficient length to receive the edges of the longest pieces of fabric which it is desired to unite. The fabric is impaled upon the pins, so that its extreme edges, in which the seam is to be taken, will project above the edge of the table, the amount of such projection, and consequently the width of the seam, being accurately determined by means of a gage, 3, 60 which is moved along from pin to pin, so that as the fabric is impaled its edges can be brought up snugly against the flange 4 of the gage, and thus be made uniform throughout the whole length of the piece. The gage 3 is 65 provided with a ring, 5, through which the operator can pass one of his fingers, so as to conveniently slide the gage along from pin to pin, and also hold it in place while impaling the edges of the fabric upon the pins. 70

The sewing mechanism proper of the machine herein shown is substantially the same as in the patents referred to, and therefore reference is made to those patents for a specific description of the same. The presser-foot 75 is, however, in the present case modified in construction. It consists of a single curved plate, 6, pivoted or hinged upon the end of the bar 7, projecting from the needle-bar carrier, and is provided with a spring, 8, so arranged 80 as to press the foot constantly inward and hold the fabric snugly against the cloth-plate 9, and yet yield sufficiently to allow any inequalities in the fabric to pass and not impede the progress of the machine. The foot 6 is provided with a slot, 10, (see Fig. 3,) to permit the oscillation of the needle, which is a necessary feature in a machine of this character. 85

The construction of the guiding frame or way upon which the machine travels has been 90 changed in order to give the machine the necessary range of travel.

In the machine shown in the patents referred to the supports for the guide-bars and driving-rack are so arranged that the machine can 95 only travel between two supports, which distance is sufficient for all the purposes for which the machine there shown is designed; but in the present case the range of travel of the machine is so great that it is necessary to provide 100 supports for the driving-rack and guide-bars between their ends. To do this, and yet not

prevent the movement of the machine, the table or counter 2 is provided at a suitable distance from its edge with a series of brackets, 13, to the top of which is fixed the rack-bar 12. The front edge of this bar is provided with a series of teeth which engage with the driving-pinion 14 of the sewing mechanism, (see Fig. 1,) said pinion and rack being kept in engagement by the anti-friction wheels 15, bearing against the opposite side of the rack-bar, and carried by arms 16, extending from the frame of the sewing mechanism above the rack-bar. The brackets 13 are also provided with short arms 17, the upper ends of which carry the prismatic guide-bar 11, which is nearly embraced by the long bearing 18 on the frame of the sewing mechanism. From this it will be seen that the supports for the guide and rack bars do not in the least interfere with the travel of the machine. When the bearing 18 is made of considerable length, as shown in the present case, it is evident that one arm and wheel, as 15 16, will be sufficient to hold the mechanism in proper position and the 25 wheel 14 in engagement with the rack 12. Consequently, although two arms and wheels are shown, one may be omitted without departing from the invention, as specified in the claims.

The apparatus for severing the thread at the 30 end of the run of the machine is in the present case the same as in Patent No. 256,518, referred to, except that in that patent the apparatus is stationary, since the end of the run of the machine is always at the same point, while 35 in the present case the apparatus is made adjustable, so that the run can be terminated and the thread severed at any point desired. To accomplish this the severing-blades 19 20 are attached to a movable carrier, 21, provided 40 with bearings which embrace the guide-bar 11 and the front edge of the rack-bar 12, as shown in Fig. 5. This permits the carrier to be moved to any desired point, it being fastened in position, when adjusted, by means of the set-screw 45 22, which impinges against the bar 11, and the spring-catch 23, which engages with the teeth upon the rack-bar.

The severing apparatus having been placed at the point where it is desired to have the run of the machine terminate, the sewing mechanism will be arrested at the proper time and the needle held in its withdrawn position, while the thread is severed by the action of the lever 24 upon the projection 25 of blade 19, all as described in the patents referred to. 50

It will readily be seen that it is not essential that the needle should reciprocate in a horizontal plane. It may be arranged vertically equally well, in which case the material operated upon will lie upon the top of the table, 60 instead of hanging from its edge.

What I claim is—

1. The combination, with the guide and rack bars, of the adjustable knife-carrier, substantially as described. 65

2. The combination, with the guide and rack bars, of the adjustable knife-carrier provided with the set-screw and spring-catch for holding it in any adjusted position, substantially as described. 70

3. In a sewing-machine which moves over the material operated upon, the combination, with the cloth-plate, as 9, of the hinged presser-foot, as 6, consisting of a single curved plate provided with the slot, as 10, substantially as described. 75

4. The combination, with the brackets, as 13, provided with the guide and rack bars, as 11 12, of the sewing-machine frame, provided with the partially-open bearing 18, and arms, as 16, 80 carrying anti-friction wheels, as 15, substantially as described.

5. The combination, with the table provided with the impaling-pins, as 1, of the movable gage 3, provided with the flange 4, substantially as described. 85

In testimony whereof I have hereunto set my hand in the presence of two subscribing witnesses.

ORVILLE R. VAN VECHTEN.
